UNITED STATES PATENT OFFICE

JULIUS B. WANTZ, OF OAK PARK, AND JULIUS J. GROBE, OF CHICAGO, ILLINOIS, ASSIGNORS TO GENERAL ELECTRIC X-RAY CORPORATION, OF CHICAGO, ILLINOIS, A CORPORATION OF NEW YORK

TUBE HOLDER

Application filed December 3, 1926. Serial No. 152,347.

The present invention relates to X-ray apparatus, and has particularly to do with an apparatus whereby a plurality of X-ray tubes may be maintained in position for substantially instant use.

For the Roentgenologist, there are two entirely different fields of endeavor, one dependent upon the other, that are very prominent and important. The first of these is that X-ray examination designated fluoroscopy, and this is intended to aid the Roentgenologist through visual examination and with the effect of X-rays upon a fluoroscopic screen, to see in shadow form the interior of the subject through which the X-rays penetrate.

While fluoroscopic examinations are highly useful in diagnostic and other work, these examinations do not give the same definiteness of results as radiographs. One of the principal uses, then, of fluoroscopic examination is as a preliminary to procuring radiographs.

Radiography gives to the Roentgenologist a light and shadow picture of the parts penetrated by X-light. It permits of analysis by the Roentgenologist of the photograph thus obtained and allows the person making such examination an extended period for study of the subject and the characteristics disclosed in the shadow picture.

Very few persons could stand the strain necessary to permit of a study which is usually required in these cases. On the other hand, the eye, by the fluoroscopic screen examination, is unable to discern many of the details which are clearly brought out by radiographs.

For fluoroscopic examination, the amount of electromotive force employed is relatively small. The X-ray tube is of a lower power than that required for radiography. It would not be desirable to subject a patient to long exposure under the X-light employed for photography for fear of burning or other deleterious effects. The electromotive force required for radiographic work is many times greater than that for fluoroscopic examinations, and the exposures are for relatively short periods.

A different character of focus is required for tubes intended for fluoroscopic examination from that for radiographic work. Usually the tube required for fluoroscopic work has what is called a sharp focus because low power is employed. The focus for radiographic work should be quite broad because the energy employed or dissipated is exceedingly large and the period of activity quite short. For treatment, other types of tubes are used.

Between the extremes discussed, other tubes are found, and it should at once be apparent that a Roentgenologist or radiologist requires under different circumstances different tubes.

So far as the information available discloses, conventional X-ray devices provide means only for employing one tube either above or below or at one side of an X-ray apparatus. The purpose of the present invention is to provide in X-ray apparatus, both of the horizontal and vertical type, a holder for a plurality of tubes, and means for bringing such tubes as required quickly into use. Means for the shifting of the tubes and the quick electrical connection thereof with the power lines is absolutely necessary in carrying out the objects of the invention.

The objects of the invention, among others, include the following:

The provision of a multiple tube holder for X-ray tubes;

A device for holding a plurality of X-ray tubes and means for quickly shifting the device so that such tubes may be brought into operable position;

A new and improved article of manufacture comprising a device for holding a plurality of X-ray tubes possessing means for shifting such tubes at the will of the operator, and means for establishing as an incident to such shifting, electrical connection whereby the desired or selected tube may become operable; and

A unique device for holding a plurality of X-ray tubes one of which is adapted to be disposed in operable position and the others in reserve, in combination with apparatus for quickly shifting such tubes at the

will of the operator, and means for establishing electrical connections with such tubes as an incident to shifting in operable position, the device including means for preventing 6 short circuiting or the probability of other electrical accidents.

These, and such others as may herein-after appear, are obtained by the novel construction of the elements constituting the 10 device, their combination one with another, and the arrangement of the several elements with respect to an X-ray apparatus.

Two forms of the invention are disclosed, one form showing a device as employed up- 15 on a horizontal X-ray apparatus and the other form adapting a device to a vertical apparatus.

Two sheets of drawings are appended, and in said drawings:—

20 Figure 1 is a side elevation of an X-ray table of conventional design upon which a multiple tube holder embodying one form of the present invention is disposed, a part of the table being broken away to save space;

25 Figure 2 is an end elevation of the device shown in Figure 1;

Figure 3 is a back elevation of a vertical X-ray device having attached thereto a multiple tube holding member, parts of the de- 30 vice being broken away for better illustration; and

Figure 4 is a side elevation of the device shown in Figure 3.

Like reference characters are used to des- 35 ignate similar parts in the drawings and in the description which follows.

Reference should be had first to Figures 1 and 2. In these figures is shown an X-ray table in elevation. The table is conventional 40 and comprises end pieces, 10 and 11, having cross members 12 and 13. Intermediate members 10 and 11 are horizontally disposed longitudinal supports 14 and 15. Also longitudinally disposed intermediate the end 45 members 10 and 11 is a table top 16 which is of material transparent to X-rays.

The parts 14 provide a suitable track for a reciprocating carriage 17 having at one side thereof a standard 18. A yoke 19 is adapted 50 to telescope upon standard 18 and a fork 20 is journalled in said yoke 19 and has disposed thereupon a screen 21 which is supported by the trunnion 22 mounted in fork 20.

The carriage 17 carries shutters 23 and 24 55 for regulating the area through which X-light may pass and adapted to be operated by rods 25 and 26 which are connected to rotatable handle members 27 and 28, one being disposed within the other, and the outer one 60 being seated for rotation in a sleeve 29 disposed on the carriage 17. The foregoing description applies to apparatus that is conventional and found in a modern X-ray table.

65 Depending from the carriage 17 beneath

the shutters 23 and 24 and secured to a platform or base 30 are two triangular brackets 31 which provide adjacent their bottom the axis of revolution for a tube holding member. The tube holding part comprises a generally triangular member 32 having detachable apices and at its geometrical center, a coupling member 33 in which is secured a shaft 34 which shaft 34 extends through and is journalled in the triangular bracket 31. One of the shafts 34 has at its end a gear 35, and at the same end and in juxtaposition thereto is a bracket 36 in which an operating shaft 37 is journalled.

Operating shaft 37 has at its end a gear 38 meshing with gear 35, and at its other end, it is journalled in a bracket 39 secured to the carriage 17. A handle 40 upon the upper end of rod 37 provides for the operation of the shaft 37 and said shaft 37 when rotated, im- 80 parts motion to the shafts 34 whereby the tube holder 32 is rotated from one position to another. Complete rotation is not necessary, as is readily apparent, but is not objectionable. For convenience, the handle 40 is placed in juxtaposition to the operating handles 27 and 28 for the shutter portions of the device.

Three X-ray tubes 41 are used with the device shown. Each of the X-ray tubes 41 is disposed within a shield comprising two parts 42 adapted to be bolted together at a flange 43. There is a window 44 in each shield 42 through which window the X-light generated by the tube 41 is adapted to be 100 projected.

The tube 41 is supplied with the usual anode and cathode if it is of the hot cathode type which type is the only type suitable for use with shields such as are here illustrated, 105 and at the ends of the tubes, special connections now to be described are provided.

It will be noted that at the right hand end of the tube 41 in Figure 1 is a threaded portion 45 of small diameter and an insulated head 46 of relatively greater diameter. At the other end of the tube is a contacting portion 47. The parts 45 and 46 are insulated one from another and are used as contacts whereby the low tension current for heating the cathode is introduced into the tube 41. The threaded part 45 or the head 46 also provide a connection for the high tension current and one is connected to the cathode for this purpose, while the part 47 provides a 115 connection for the other side of the high tension current with which the tube is adapted to be operated.

Within the right hand member 31 (Figure 1) is a bracket 48 having an extension portion 49 adapted to be secured to the base or platform 30. To this bracket is secured a connector 50 which is adapted to engage the threaded portion 45 of tube 41. There is also mounted in the bracket 48, a connector 51 120

which is adapted to establish electrical connection with the part 46 upon the tube 41.

Connectors 50 and 51 may be spring actuated or of any other desirable construction whereby they form an intimate contact with the parts 45 and 46 of a tube 41 when such tube is brought into usable position by proper rotation of the triangular members 32.

At the opposite end of the device, or the 10 left hand end of Figure 1, and upon the left hand part 31 is another bracket designated 52, which bracket may be provided with an insulated sleeve 53 through which a high tension cable may be run. At the end of the 15 sleeve 53 is a contact 54, spring actuated or otherwise operated, whereby it is adapted to securely engage the part 47 of a tube 41 when in operable position. The cables 55, 56, and 57 are adapted to be electrically connected 20 with the contacts 54, 51, and 50 respectively.

For convenience, a bracket 58 may be provided in juxtaposition to the left hand member 31 (Figure 1) and upon said bracket are disposed cable bushings 59 to accommodate

25 cables 56 and 57. At the extreme left hand end of Figure 1, are several cord reels, designated 60, over which the cables 55, 56 and 57 are adapted to pass, as an incident to connection with the contacts heretofore described.

30 It is well known in the X-ray art to provide cords and cord reels or pulleys whereby the high tension wires may be automatically drawn out of a position where contact therewith is likely to occur. The present apparatus

35 is of the type indicated and the various pulleys here described and particularly pulley 60, are for the express purpose of accommodating the needs of an X-ray table with respect to electrical conduits.

40 As previously indicated, the member 32 has removable apices, designated 32a. The peripheral surface of the member 32 adjacent such apices is cut away to form a semicircular depression and the material of the removable

45 and detachable apices 32a is likewise cut away. The two removed portions are complementary and thus afford means for mounting an X-ray tube shield. The parts 42 are adapted to be held securely between the mem-

50 ber 32 and the detachable holding portions 32a, suitable screw members being adapted to pass through the parts 32a into the body of the triangular member 32.

55 From the preceding description, the operation of the multiple tube holder disclosed in Figures 1 and 2 is quite apparent. When a tube 41 is required or desired for use, the handle 40 is rotated until the selected tube is 60 brought into its proper position beneath the shutters 23 and 24. As an incident to its rotation into proper position, the ends of the tube 41 are brought into contact with the members 50 and 51 at one end thereof and the 65 member 54 at the other end whereby the

necessary electromotive force to operate the tube may be introduced therein.

When another of the tubes 41 held in the device is desired, the handle is operated until such other tube is brought into position and 70 the contacts previously described obtained. As has been pointed out, the members 32 need not be mounted for complete rotation. There may be what is called a middle tube and two end tubes, the magnitude of the rotation of 75 the parts 32 being the arc intermediate the position which one end tube occupies when in operable position to the position the same tube occupies when the other end tube is in operable position.

80 In Figures 3 and 4, a vertical X-ray device is disclosed. In this type of apparatus it may be desirable to employ a series of tubes held in alignment rather than in the manner described hereinabove. When so held, the shifting of the tube holder may be in a straight line rather than with a rotary motion as is necessary in the type of device shown in Figures 1 and 2.

85 The device disclosed in Figures 3 and 4 comprises a conventional vertical fluoroscopic and radiographic stand. The stand comprises the base 70 and the uprights 71 and 71a. Connected to the uprights 71 and 71a at their top is a casting or other suitably formed member 72. Transverse brace members 73 may be employed in conjunction with the apparatus for adding strength thereto.

90 Upon brackets 74 and 75, generally disposed upon the uprights 71, is a sheet of material 76, transparent to X-light, and against which the object to be examined or photographed, generally a human being, is stood during the course of fluoroscopic examination or radiographic reproduction. As is not uncommon in vertical X-ray apparatus, the patients' support 76 may not be truly vertical.

95 Upon the members 71 and adapted to be moved vertically and reciprocatingly is a carriage 77. From this depends the tube 100 holder which forms the subject matter of this application for patent, and the fluoroscopic screen fully illustrated in Figure 4. The carriage 77 is counterbalanced by a weight 78 carried upon a cable 79, such cable passing 110 over the pulleys 80 on the top member 72.

115 From brackets 81 projecting upwardly from the carriage 77 a fluoroscopic screen depends. The means for mounting the fluoroscopic screen comprises members 82 horizontally slidable upon said brackets 81 and from which depend a forked member 83 forming a pivot mounting for a fluoroscopic screen 84. Suitably disposed with respect to the carriage 77 are shutters such as are described hereinabove and illustrated in Figures 1 and 2. For convenience such shutters in the vertical apparatus are designated 85. Said shutters 85 are actuated by operating handles 86 and 120 87 through which rods 88 and 89 may be 130

actuated. Disposed about said operating handles 86 and 87 is a third operating handle 90, the handle being of a generally knurled configuration. Handle 90 rotates a tubular shaft 91 to which a gear 91a is keyed.

The tube holding member is designated 92. Depending therefrom are brackets 93, 94, 95, 96, 97 and 98. In these brackets are disposed X-ray tubes. Each of the X-ray tubes when disposed in the brackets referred to above, is held within shields comprising two parts designated 99 and 100.

The brackets 93 to 98 inclusive for supporting X-ray tubes are preferably of insulating material and the shield parts 99 and 100 are also of insulating material. Because of the use of insulating material in the manner just described, there is no possibility of "shorting" the high tension electromotive force employed in operating the tubes when in the apparatus.

Carriage 92 is adapted to be reciprocated transversely of carriage 77 so that the tubes contained in the brackets previously mentioned may be brought one at a time, into a position at approximately the center of the carriage 77. A gear rack 101 is arranged to mesh in gear 91a and said gear rack 101 is directly secured to the carriage 92. Said rack 101 moves the carriage 92 whereby it is forced to move relatively to the carriage 77. Rotation of the handle 90 therefore brings the several tubes contained in the paired brackets above referred to into operable position at the will of the operator.

Adjacent the carriage 92 is a bracket 104. At the free end thereof is a contact 105 of the plunger type or spring actuated and which is electrically connected to a cord or cable 106 passing about a cord reel 107. At the other end of the tube carrier 92 is a second bracket 108 having an extension 110 upon which two cable bushings 111 are disposed.

Upon the cross member 109 are two contacts 112 and 113, both carrying low tension current for heating the filament in the tubes. One of the contacts 112 or 113 is in electrical circuit with a source of high tension power for energizing the tube.

One of the contacts 112 or 113 is adapted to impinge the collar 114 upon the X-ray tube. Insulating material is used in conjunction with the tube for the purpose of insulating said collar 114 from a threaded portion 115 closely adjacent thereto. Cords 116 and 117 pass about cable bushings 118 and cord reels 119 to a source of electromotive force and thus an electrical connection between such source of power and the contacts is established. By rotating the handle 90 in one direction or the other the tube carrier of the vertical fluoroscopic and radiographic device here illustrated is adapted to be reciprocated horizontally in one direction or the other until the tube selected for the examina-

tion or operation is brought into an operable position in juxtaposition to the shutters 85 hereinabove described. An instant change of tubes is accomplished by merely rotating the handle 90 the desired number of turns.

In either form of the device illustrated, means may be supplied whereby the electro-motive force for energizing the X-ray tube may be automatically cut off as an incident to a change or contemplated change in tubes. This is a matter of safety. A plunger actuated switch can readily be supplied which switch will be adapted to open as an incident to any lateral movement of the carriage 92.

What we claim is new and desire to secure by Letters Patent is:

X-ray apparatus comprising a tube having a conducting sleeve and a conducting head insulated therefrom at one end, and a conducting sleeve at its other end, a shiftable holder for such tube, means for moving said holder, and a series of spring actuated contacts for establishing electrical connection with said tube sleeves and head as an incident to such tube being moved into a predetermined operable position.

JULIUS B. WANTZ.
